SURGE FILTER FOR PULSATING GASES

Ralph L. Leadbetter, Wheaton, Ill., assignor, by
mesne assignments, to Burgess Battery Com-
pany, Chicago, Ill., a corporation of Delaware

Application October 24, 1938, Serial No. 236,635

7 Claims. (Cl. 131—54)

This invention relates to surge filters for flowing, pulsating gases, such as the exhaust gases of internal combustion engines, or, as the terms are loosely used, to improvements in mufflers and 5 silencers for such pulsating gas systems.

Although the invention is useful for the prevention of noise caused by pulsating gases generally, including, for example, the intake and delivery of air compressors, the most severe conditions are met in the prevention of noise caused 10 by the exhaust of internal combustion engines and for this reason the invention will be illustrated and described as applied to this particular problem.

15 A large variety of constructions have heretofore been employed for the attenuation of noise resulting from the operation of internal combustion engines. Whether such mufflers employ baffles, resonating chambers, or equalizing or ex- 20 pansion chambers, an analysis of their operation discloses that their function depends entirely upon pressure fluctuations of the gas stream and thus their effectiveness depends upon their proximity to points of maximum pressure change in 25 the exhaust system. Thus a resonating chamber tuned to attenuate a particular frequency is inoperative when located at a (velocity) antinode of that particular sound wave which it is designed to attenuate. It will be seen from the 30 following detailed description that the present invention constitutes a radical departure from mufflers and silencers heretofore known for the reason that it operates by virtue of the inertia imparted to the gases upon being ejected from 35 the engine cylinder into the exhaust system. The invention operates as a velocity smoothing device and depends upon pressure only in the remote sense that the inertia of the exhaust gases depend upon a static pressure in the en- 40 gine cylinder at the time the exhaust valve is opened.

The fundamental distinction indicated in the preceding paragraph will become more apparent as the description of the invention proceeds.

45 The object of this invention is to prevent noise caused by flowing, pulsating gases by means of a device that may be located with equal effectiveness at any point in the conduit carrying the gas stream and to reduce back pressure and 50 eliminate so-called "period" noises.

The essential element of a muffler embodying this invention is a receptacle or "snubber chamber" into which the pulsating gases are projected at high velocity from the exhaust ports of an 55 engine or other source. This snubber chamber

is equipped with impedance means for cushioning the progress-interruption of the gas spurt accomplished by the snubber chamber and to prevent unhampered rebounding of the pulsation from the mouth of the snubber chamber back 5 into the conduit. Part of the gases are shunted by the snubber chamber entrance; only that portion of each pulsation having sufficient inertia to cause it to jump a gap rather than deviate in its course to follow the shunt enters the snubber chamber. The velocity of the gases entering the snubber chamber is arrested and the gas pressure caused thereby dissipated by a relatively gradual restoration of the gases to the 10 system.

15 In the accompanying drawing,

Fig. 1 is a longitudinal sectional view illustrating the elements of a device constructed in accordance with the present invention;

Fig. 2 is a longitudinal sectional view of a 20 muffler embodying the invention, and

Fig. 3 is a transverse sectional view of the muffler of Fig. 2 taken at line 2—3.

The exhaust of an internal combustion engine consists largely of a series of rapidly traveling 25 pulses of high pressure gas known to the art as "slugs." A high velocity peak, or slug, is formed each time an exhaust valve opens. Sound waves are thought to be caused by high velocity impact of these slugs with the atmosphere. These are 30 the sharp cracks characteristic of the exhaust when not properly muffled. A low pitched rumble is maintained between explosions. These noises may be eliminated by dissipating the velocity peaks to smooth out the flow of the gases 35 through the exhaust system before exhausting to the atmosphere. In addition to these noises, period noises are caused at certain firing frequencies of the engine. These periods occur when the firing frequency substantially coincides 40 with the natural resonant frequency of the exhaust system or a harmonic thereof, the timed recurrence of the pulsations tending to set the exhaust system in vibration. Periods may also occur when the exhaust slugs reinforce every 45 second, or every third, etc., sound wave condensation without intervening neutralizing slugs.

Noise of the exhaust system due to resonance of the pipe depends largely upon reflection of the atmospheric impact into the system. The 50 muffler of this invention is effective in preventing such impacts and thus in preventing both direct and period noises.

The device illustrated in Fig. 1 consists of a shell enclosing chamber 1 into which extends 55

perforated impedance member 2, the latter being in alignment with inlet conduit 3 and, optionally, round or oval in cross section. A tail pipe 4 connects with by-pass chamber 4a. The only entrance into chamber 1 is via impedance member 2. The area of gap b between contiguous ends of conduit 3 and member 2, that is, the area of the surface generated by drawing lines from points on the periphery of the inner end of conduit 3 to the nearest points of the periphery of the mouth of member 2, should not be substantially less than the cross-sectional area of inlet conduit 3. Restated, and by way of example, if conduit member 3 and impedance member 2 are circular in transverse section and have the same diameters, b should not be substantially less than one-fourth a. With this relationship it will be seen that a substantially unrestricted passageway is provided through which the gases may flow, as indicated by the arrows, without entering snubber chamber 1. This unrestricted passageway is the "shunt" path referred to above.

In the operation of the device, the gas slugs are projected through inlet conduit 3 toward snubber chamber 1. The path of least resistance would be from the inlet conduit directly to outlet conduit 4 through by-pass chamber 4a, but a portion of each slug has sufficient inertia imparted by the extremely high pressure conditions within the cylinder of the engine at the moment the exhaust valve opens to cause that portion of the slug to enter snubber chamber 1 via perforated member 2. The velocity energy of the slug is transformed into static pressure within impedance member 2 as the slug is brought to a cushioned stop, the pressure being dissipated by an expansion of the gases into the space of chamber 1 surrounding member 2 through the perforations in the latter. When the velocity energy of the slug has been spent in this way, the pressure conditions within chamber 1 cause a restoration of the gases to the by-pass chamber via the perforations in impedance member 2. As hereinbefore suggested, the purpose and function of member 2 is to impede the flow of gases into, and to prevent an unimpeded rebound of the slug from, chamber 1, resulting, rather, in a relatively gradual introduction of gases into the chamber and a relatively gradual restoration of the gases from this chamber to the by-pass chamber 2. A snubber effect is thereby obtained which reduces the gas-velocity-peaks of the flowing gases whereas a chamber without the impedance means described would merely reflect and possibly aggravate the pulsations. Additionally, it may be noted that the time lag caused by the impedance and the cooling (and therefore contraction) of the expanding gases materially aid the snubbing operation in reducing the magnitude of the velocity peaks.

No representation is made that the device above described is alone capable of preventing or attenuating pulsating gas noises to a degree considered satisfactory to the art except in certain cases. This device is efficient in the smoothing of the gas flow and therefore in the removal of the cause of noise. In particular, sounds in the lower frequency ranges are prevented by virtue of the invention. However, the device is intended to be used in conjunction with means for attenuating the high frequency sounds. A simple expansion chamber or a "packed" muffler constructed in accordance with the disclosure of

75 Schnell Patent No. 1,811,762, dated June 23, 1931,

may be used for this purpose. Such a unit may be connected either in conduit 3 or in conduit 4.

A construction in which the snubbing unit above described is combined with a simple expansion chamber is shown in Figs. 2 and 3. A cylindrical shell 5 is provided with end flanges 6 and 7 having inlet opening 8 and outlet opening 9 therein, respectively. Inlet snout 10 is mounted in end flange 6 at inlet opening 8 and exhaust snout 11 is mounted at opening 9 in end flange 7. A partition 12 having an opening 13 therein in alignment with inlet opening 8 and an opening 14 not in alignment with inlet opening 8 is arranged transversely within shell 5 in spaced relation to inlet end flange 6 to form by-pass chamber 15. A shell 16, including closure member 17, defines snubber chamber 18 into which an impedance means in the form of a perforated, closed-ended tube 19 projects. The latter opens into by-pass chamber 15 at opening 13. The snubber chamber 18 is entirely closed so that gases may enter it only via opening 13 and perforations 20. The gases must leave this chamber by the same path. Perforated conduit 21 connects by-pass chamber 15 with the outlet opening 9 and may be integral with exhaust snout 11, as shown. The perforations in the walls of conduit 21 permit expansion of the gases traveling through the conduit into space 22.

The operation of the snubbing unit of the device of Figs. 2 and 3 is as above described. The high velocity portion of a slug entering the device through inlet snout 10 jumps the gap c and is snubbed in the snubbing chamber 16. The remainder of the gases by-pass from opening 8 directly to conduit 21 and are exhausted to the atmosphere. The gases entering into and operated upon by the snubbing unit are gradually restored to by-pass chamber 15 whence they flow through conduit 21 to the atmosphere. Expansion chamber 22 cooperates with the snubber unit in removing or preventing substantially all of the noises which would otherwise be caused by the pulsating gases.

Gap c should be sufficiently large to permit substantially unrestricted flow of gases through the device via openings 8, 14 and 9. While the degree of perforation of impedance members 19 and 2 (Fig. 1) is not critical, they should be sufficiently open to permit the proper degree of expansion of the gases entering them into the surrounding space. Excessive perforation would result in the loss of the necessary impedance to the flow of gases into the snubber chamber and the reflection of pulsations therefrom. Empirical findings indicate that the impedance member should be perforated sufficiently to provide a total open area of 5 per cent of, to 4 times, the cross-sectional area of the inlet snout or exhaust pipe leading to the muffler. The snubber chamber itself should be sufficiently large to permit substantial expansion of the gases into it from the impedance member.

Without limiting the invention and by way of example it is noted that a muffler constructed substantially as shown in Figs. 2 and 3 and having the following dimensions operated satisfactorily in preventing exhaust noise from a single cylinder, four cycle internal combustion gasoline engine of 2-horse-power at 1800 revolutions per minute having a cylinder bore of 2 $\frac{1}{2}$ inches and stroke of 2 $\frac{1}{2}$ inches: shell 19 inches long by 4 inches in diameter, gap c 1 $\frac{1}{2}$ inches, impedance member 16 inches long by 1 inch in diameter and perforated sufficiently to provide walls 4 per

cent open, diameter of snubber chamber $2\frac{3}{4}$ inches.

This invention is adaptable to embodiment in various forms not specifically shown or described herein but following the principles thereof. For example, inner shell 18 may be concentric with perforated conduit 21 thus providing a snubber chamber occupying the entire volume of outer shell 5 except that enclosed by the imperforate inner shell. The term "perforated" is intended to cover all equivalent constructions wherein the member may be apertured otherwise than by stamping out small round portions of the material. Although the impedance means is illustrated as elongated and tubular, it is clear that this member may take other suitable forms. The invention is limited only by the scope of the appended claims.

I claim:

1. In a device of the character described, gas-velocity-peak snubbing means comprising means forming a snubber chamber having substantially impervious walls, means forming a by-pass chamber, gas-flow impedance means arranged within said snubber chamber and having an entrance exteriorly thereof opening into said by-pass chamber, a conduit extending toward said impedance means entrance for conducting pulsating gases toward said entrance, said conduit terminating short of said impedance means entrance within said by-pass chamber, and means for egress of gases from said by-pass chamber.

2. A device in accordance with claim 1 in which said conduit terminates short of said impedance means entrance by such a distance that the area of the gap between the entrance to said impedance means and the contiguous end of said conduit is not substantially less than the cross-sectional area of said conduit.

3. In a device of the character described, gas-velocity-peak snubbing means comprising a shell having an opening in a wall thereof, a transverse partition within said shell dividing the volume thereof into a snubber chamber and a by-pass chamber, said partition having an opening therein in alignment with said shell wall opening, gas-flow impedance means within said snubber chamber having an entrance at said opening in said partition, an inlet conduit extending through said shell wall opening and terminating in said by-pass chamber short of said impedance means entrance, and an exhaust conduit connecting said by-pass chamber with the atmosphere.

4. In a device of the character described, gas-velocity-peak snubbing means comprising a shell having an opening in a wall thereof, a transverse partition within said shell dividing the volume thereof into a snubber chamber and a by-pass chamber, said partition having an opening therein in alignment with said shell wall opening, a perforated tube extending into said snubber

chamber from the periphery of said opening in said partition the end of said tube within said snubber chamber being substantially closed, an inlet conduit extending through said shell wall opening and terminating in said by-pass chamber short of said perforated tube entrance, and an exhaust conduit connecting said by-pass chamber with the atmosphere.

5. In a device of the character described, a cylindrical shell having end closures and a transverse partition therewithin, a concentric opening in an end closure and a concentric opening in said partition, impedance means having an entrance at said opening in said partition and extending into the space within said shell away from said end closure having an opening therein, a conduit connecting with a source of pulsating, flowing gases and extending through said opening in said end closure, said conduit terminating short of said impedance means entrance, and an exhaust conduit connecting the space between said partition and said end closure having an opening therein with the atmosphere.

6. In a device of the character described, an outer shell having inlet and outlet end closures having inlet and outlet openings therein, respectively, a transverse partition arranged within said outer shell in spaced relation with said inlet end closure to form a by-pass chamber and having an opening therein in alignment with said inlet opening, an inner shell dividing the space within said outer shell and between said partition and said outlet end closure into a snubber chamber communicating with said by-pass chamber by means of said opening in said partition and an expansion chamber, a tubular member having perforated walls within said snubber chamber opening into said by-pass chamber at said opening in said partition the opposite end being substantially closed, and a perforated conduit passing through said expansion chamber and connecting said by-pass chamber with said outlet opening.

7. In a device of the character described, an outer cylindrical shell having inlet and outlet end closures having inlet and outlet openings therein, respectively, a transverse partition arranged within said outer shell in spaced relation with said inlet end closure to form a by-pass chamber and having an opening therein in alignment with said inlet opening, a perforated tubular member extending from said partition at said opening therein away from said inlet opening, the end of said tubular member remote from said partition being covered by a perforated closure member, an inner shell surrounding said perforated tubular member and providing a space between said tubular member and said inner shell, and a perforated conduit within said outer shell and without said inner shell connecting said by-pass chamber with said outlet opening.

RALPH L. LEADBETTER.
